UNITED STATES PATENT OFFICE.

SAMUEL K. GROVER, OF PROVIDENCE, RHODE ISLAND.

DESIGN FOR A HAT-PIN.

SPECIFICATION forming part of Design No. 33,451, dated October 30, 1900.

Application filed October 3, 1900. Serial No. 31,930. Term of patent 34 years.

To all whom it may concern:

Be it known that I, SAMUEL K. GROVER, a citizen of the United States, residing at Providence, in the county of Providence and State of Rhode Island, have invented and produced a new and original Design for a Hat-Pin, of which the following is a specification, reference being had to the accompanying drawings, forming part thereof.

Figure 1 is an end view of a hat-pin, showing my new design. Fig. 2 is a side view of the pin and a transverse sectional view, on an enlarged scale, on the line X X of Fig. 1.

As shown in the drawings, the leading or material feature of my design consists in the outline and configuration of the head, representing a soaring bird, the wings and body of which are studded with brilliants. The head of the pin has the outline of a bird with expanded wings having the convex marginal edges *a*. The brilliants *b* are set into the crown-shaped clamp-settings *c*. The head of

the bird has two brilliants in positions indicating the eyes. Rows of brilliants are arranged along the outer margin of the wings. 25 The body has three rows of the brilliants, the central one of which divides into two branches, extending over the two sides of the tail. The surface of the head is covered with slightly-raised figures resembling feathers, the head 30 of the hat-pin resembling a soaring bird studded with brilliants.

Having thus described my invention, what I claim as new, and desire to secure by Letters Patent, is—

The design for a hat-pin as herein shown and described.

In testimony whereof I have signed my name to this specification in the presence of two subscribing witnesses.

SAMUEL K. GROVER.
